UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Application filed July 8, 1925. Serial No. 42,284.

My invention relates to mining machines and more particularly to mining machines of the continuous cutter type adapted to be fed laterally relatively to the face of the coal to 5 cut a horizontal kerf thereunder.

Mining machines of the continuous cutter laterally fed type are particularly adapted for use in the room and pillar system of mining. They are usually propelled by means of 10 a flexible feeding member which is anchored at its free end at the advancing side of the machine and acted on by a feed operating member driven by the mining machine motor. A second flexible member is provided and is 15 anchored at the receding side of the machine and paid out as the machine advances under control of a suitable retarding or controlling device. The purpose of this second flexible member is to maintain a proper position of 20 the machine relative to the face of the coal.

A main object of my invention is to provide a mining machine of the continuous cutter room and pillar type which is of an extremely low and compact character especially 25 adapted for use in mines having low veins or seams of coal. Another object of my invention is to provide an improved continuous cutter room and pillar mining machine of the "low vein" type having an improved compact 30 general arrangement of parts.

In a preferred form the invention comprises a mining machine of the continuous cutter room and pillar type having a plurality of rope drums one of which is adapted to 35 be normally driven and the other of which is provided with a retarding means comprising a friction controlled releasing device, the power driven drum being driven from the motor through improved variable speed transmission means of an exceedingly compact 40 character whereby a machine of extremely low height is obtained especially adapted to use in mines having low veins of coal. In a preferred embodiment the feeding mechanism comprises a feed drum rotatable on a vertical axis and driven through two speed variable friction controlled mechanism comprising planetary gearing rotatable about a vertical axis parallel with the axis of the feed 45 drum and driven from the driving motor 50

through improved, simplified, and compact connections. The machine is provided with a forwardly projecting elongated cutter bar extending longitudinally of the machine throughout cutting and adapted to cut a horizontal kerf in the coal and about which an endless cutter bit carrying cutter chain is adapted to be circulated, the cutter chain being driven from the driving motor through transmission means associated with the feed 55 transmission and likewise of an exceedingly low and compact character. The feeding means and cutting mechanism are disposed within the forward end of the machine frame while the driving motor is located at the rear 60 end of the machine frame and the height of the machine is substantially determined by the height of the motor.

In the accompanying drawings I have shown for purposes of illustration one form 70 which my invention may assume in practice.

In these drawings,—

Fig. 1 is a top plan view of my improved mining machine, a portion of the frame being broken away to facilitate illustration of certain details.

Fig. 2 is a vertical longitudinally extending sectional view taken substantially on line 2—2 of Fig. 1, the view being shown partially in elevation.

Fig. 3 is a side elevational view of the forward end of the advancing side of the machine, the view being partially broken away in section to facilitate illustration of certain details of construction.

Fig. 4 is a transverse vertical sectional view taken substantially on line 4—4 of Fig. 1.

Fig. 5 is an enlarged sectional view taken on line 5—5 of Fig. 3 and illustrating the planetary change speed mechanism.

In this illustrative embodiment of my invention I have shown a mining machine designated as an entirety by the numeral 1, herein of the flexibly fed room and pillar type, comprising a machine frame 2 slidable on its bottom 3 on the mine bottom. As shown, rigidly secured within the forward end of the machine frame 2 at one side of the longitudinal center line thereof, is a horizontally disposed forwardly projecting rigid cutter 100

bar 4 about the outer edges of which an endless cutter bit carrying cutter chain 5 is adapted to be circulated through improved transmission means hereinafter more fully explained. The machine is adapted to be propelled along the mine bottom by means of a flexible feeding means including a flexible feeding element 6, herein in the form of a cable or rope, the free end of which is adapted to be anchored at a point in advance of the advancing side of the machine and to be wound upon a feed drum 7 rotatable on a vertical axis, as at 8, adjacent the forward end of the advancing side of the machine. The drum 7 is adapted to be driven through improved simplified and compact transmission means hereinafter more fully described. As illustrated, mounted upon the rear end of the machine frame is a second drum 9 rotatable on a horizontal longitudinally extending axis and rotation of this drum is adapted to be controlled by means of a suitable friction device 10, herein in the form of a brake band. A flexible element 11, herein in the form of a cable or rope, is wound on the drum 9 and the free end of this cable is adapted to be anchored at a point located in the rear of the receding side of the machine.

In my improved construction it will herein be noted that a driving motor 12 is disposed at the rear end of the machine and rests directly on the mine bottom and the height of this motor determines substantially the height of the machine, the motor being of an especially low compact design. This motor is preferably of the reversible electric type and is provided with an armature rotatable on a horizontal longitudinally extending axis and a forwardly projecting armature shaft 13 journaled within suitable bearings within the machine frame. In specifically describing my improved cutter chain driving mechanism it will be noted that the armature shaft 13 has keyed thereto, as at 14, a spur gear 15 which is adapted to be connected in operative driving relation with an alined spur gear 16 by means of a reciprocable clutch shipper gear 17 of well known form. As illustrated, the gear 16 has secured thereto a bevel pinion 18 which is meshed with a large bevel gear 19 formed on a hollow vertically disposed shaft 20 journaled at its opposite ends in suitable ball bearings 21 carried by the machine frame 2. Formed intermediate the ends of the shaft 20 and above the gear 19 is a spur pinion 22 rotatable in a horizontal plane and meshing with a large spur gear 23 rotatable on a vertically disposed shaft 24 disposed in the central longitudinal vertical center line of the cutter bar and having its axis in a plane parallel with the vertical longitudinal plane of the driving motor 12. The spur gear 23 is provided with a depending cylindrical sleeve 25 which is connected by a semi-permanent clutch 26

with the hub of a usual cutter chain driving sprocket 27 disposed within a recess, herein-after described, formed in the frame 2. The cutter chain sprocket and the spur gear 23 are journaled on suitable vertically spaced ball bearings 28 disposed coaxially with the shaft 24. The cutter chain sprocket 27 is adapted to drive the cutter chain 5 through the improved transmission means above described when the clutch 17 is connected, or remain idle at the will of the operator.

In specifically describing my improved feeding mechanism it will herein be observed that the armature shaft has secured thereto intermediate its ends and in the rear of the spur gear 15 a suitable worm 29 which is meshed with a worm gear 30 secured to a vertically disposed shaft 31 journaled at its opposite ends within suitable ball bearings 32 carried by a removable cover plate 33, carried by the top of the machine frame, and a housing member 34, respectively. As illustrated, the housing member 34 is provided with a reservoir 35 which is adapted to be filled with lubricant thus forming a bath within which the gears 29 and 30 are adapted to run. Furthermore, secured to the shaft 31 in a plane above the worm gear 30 is a spur pinion 36 rotatable in a horizontal plane and meshing with an intermediate spur gear 37 journaled on a vertically disposed shaft 37^a parallel with the shaft 31 and carried by the cover plate 33. The gear 37 meshes with a large spur gear 38 disposed coaxially with a vertically disposed shaft 39, the latter being journaled in suitable bearings within the top and bottom of the machine frame. Moreover, the gear 38 is adapted to drive a coaxially disposed spur pinion 40 rotatable in a horizontal plane below the plane of the gear 38 through a frictionally controlled planetary change speed mechanism generally designated 41, which may be of any approved form, located adjacent the advancing side of the machine and which is herein of the type clearly described in my copending application, Serial No. 651,830, filed July 16, 1923. The planetary change speed mechanism 41 specifically comprises a central jaw clutch member 73 longitudinally slidable on and keyed to the vertical shaft 39 and this clutch member is adapted when in its extreme upper position of movement to engage a mating clutch member 74 keyed to an annular frame member 75 carrying sets of coaxial planet gears 76. The upper planet gears mesh with a central spur gear 77 driven by and rotatable with the spur gear 38. The upper planet gears also mesh with an internal gear 78 fixed to a rotatably mounted casing 79 while the lower planet gears mesh with a second internal gear 80 fixed to a rotatably mounted member 81 having jaw clutch teeth 82 adapted to be engaged by the clutch member 73 when the

latter is moved to its extreme lower position. The brake band 43 is adapted to hold the casting 79 against rotation when desired. In operation of the device, when high speed is desired the members 73 and 74 are engaged to thereby cause the gear 38 and the gear 77 to drive the planet gears 76 around the gear 78 which is held stationary by the brake band 43. Movement of the planet gears 76 thus causes rotation of the gear carrying frame 75 which being connected to the member 73 will directly drive the vertical shaft 39 without in any way using the lower planet gear. When low speed is desired members 73 and 82 are engaged and by holding the casting 79 the member 81 is rotated due to the different diameters of the planet gears. It will thus be evident that the planetary change speed mechanism is frictionally controlled at all speeds and is adapted to drive the pinion 40 at a predetermined fast speed or a predetermined slow or cutting speed under the control of a suitable reciprocable shipper mechanism 42 and at any variants of those speeds under the control of a suitable brake band 43. Driven by the pinion 40 is an intermediate spur gear 44 rotatable on a vertical axis within the machine frame and this gear is meshed with a spur gear 45 connected in any suitable manner in operative driving relation with the feed drum 7.

From the foregoing description, it will herein be evident that the drum 7 may be driven from the driving motor selectively at a predetermined fast or at a predetermined slow speed or at any desired variants of those speeds under the friction control of the brake band 43. It will herein be noted that the cable 6 passes from the drum 7 around a guide sheave 46 rotatable on a vertical stud 47 disposed at the forward advancing corner of the machine frame.

Referring now to the means for discharging the cuttings brought back by the rapidly moving cutter chain, it will herein be observed that the forward end of the machine frame is provided with a recess 48 as clearly shown in Fig. 1 and this recess opens through the receding side of the machine frame. The boundaries of the recess 48 comprise a top wall 49, bottom wall 50, and a vertically disposed side wall 51. The side wall 51 comprises a slightly outwardly flared portion 52, an arcuate portion 53, and a straight portion 54, thus forming a recess which permits the cuttings to be discharged freely from the receding side of the machine frame as the machine advances.

Associated with the cutter chain clutch 17 is a shipper yoke 55 pivoted, as at 56, on a vertical axis and having secured thereto a worm rack 57 which is meshed with a worm 58 secured to a horizontal operating shaft 59 suitably journaled within a suitable bracket secured to the side of the interior of the ma-

chine frame 2. The shipper yoke 55 is adapted to be actuated by means of a hand wheel 60 disposed at the rear end of the machine frame at one side of the drum 9. Associated with the variable speed device 41 is a shipper yoke 61 pivoted, as at 62, upon the side of the machine frame and this shipper yoke is adapted to be swung about its pivot by means of an eccentric 63 suitably secured to a horizontal operating shaft 64 which in turn is adapted to be actuated by means of a hand wheel 65 disposed at the rear end of the machine frame at the side opposite from the hand wheel 60. As illustrated, the brake band 43 is adapted to be applied or released by means of a suitable operating screw 66 formed on a transversely disposed horizontal shaft 67. The shaft 67 has secured thereto intermediate its ends a worm gear 68 which is meshed with a worm 69 secured to a longitudinally extending horizontal operating shaft 70. The operating screw 66 is adapted to be actuated by means of a hand wheel 71 disposed at the rear end of the machine frame adjacent the handwheel 65. It will herein be noted that disposed at the side of the driving motor 12 is a casing 72 which is adapted to house usual controlling and resistance devices (not shown) of well known form for the motor 12.

In the operation of my improved mining machine, it will herein be noted that after the machine has been transported into the room on its truck and unloaded therefrom in a well known manner, the feed cable 6 is extended to a suitable roof jack located at the right hand rib of the room adjacent the face and the fast speed planetary mechanism is suitably connected to the motor and the cable 6 wound in by the drum at a fast or haulage speed, consequently propelling the machine along the mine bottom toward the roof jack. The machine is then suitably located adjacent the face of the coal, the cutter connected to the motor, and the bar sumped or fed under the coal at the desired cutting speed likewise under control of the planetary device 41. The feed cable 6 is then extended to a suitable roof jack located at the left hand rib of the room adjacent the coal face, while the controlling cable 11 is extended to a suitable roof jack located at the receding side of the machine adjacent the right hand rib. The machine is then straightened up and fed transversely across the face under the control of the planetary variable speed device 41. At the end of the transverse cut the machine is angled and withdrawn from the face in a well known manner.

As a result of my invention an improved mining machine of the continuous cutter "low vein" room and pillar type is provided of an exceedingly low compact character having improved feeding and cutting mechanism therefor. It will further be noted that an

improved machine is provided having an improved arrangement of the transmission means for the feed drum whereby the overall height of the machine is reduced to a minimum. Other advantages will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a horizontally disposed motor having a casing slidable directly on the mine bottom during operation of the machine, feeding means for the machine comprising a variable speed device disposed on a vertical axis and driven from the forward end of said motor, and cutting mechanism driven by said motor including a horizontal plane cutter bar disposed in planes adjacent the mine floor, the top plane surface of said bar lying in a horizontal plane intersecting said motor and said variable speed device.

2. In a mining machine, a horizontally disposed motor, cutting mechanism driven thereby including a forwardly projecting cutter bar, and feeding means for the machine comprising a variable speed planetary controlling device disposed on a vertical axis and driven from the forward end of said motor, and a feed operating member driven thereby and disposed in advance of the rear end of said cutter bar on the advancing side of the machine, said feed operating member being adapted to cooperate directly with flexible feeding means.

3. In a mining machine, a horizontally disposed motor having a casing slidable directly on the mine bottom during cutting, cutting mechanism driven by said motor including a forwardly projecting cutter bar, and feeding means for the machine comprising a variable speed device disposed on a vertical axis at the rear of the rear end of said cutter bar and driven from the forward end of said motor, and a feed operating member driven thereby and disposed in advance of the rear end of said cutter bar on the advancing side of the machine, said feed operating member being adapted to cooperate directly with flexible feeding means.

4. In a mining machine, a horizontally disposed motor, cutting mechanism driven thereby including a horizontally projecting plane cutter bar, and feeding means for the machine comprising a variable speed planetary controlling device disposed on a vertical axis and driven from the forward end of said motor, the upper horizontal surface of

said cutter bar lying in a horizontal plane intersecting said motor and said planetary device.

5. In a mining machine, a horizontally disposed motor, cutting mechanism driven from the forward end thereof and including a forwardly projecting cutter bar, and feeding means for the machine including a two-speed planetary variable speed device driven from the forward end of said motor, and a feed operating member rotatable about a vertical axis driven by said device and disposed on the advancing side of the machine in advance of said planetary device, said feed operating member being adapted to cooperate with flexible feeding means.

6. In a mining machine, a horizontally disposed motor having a casing slidable directly on the mine bottom during operation of the machine, the height of the machine being determined substantially by the height of the motor, cutting mechanism driven from the forward end of said motor including a forwardly projecting cutter bar, and feeding means for the machine driven from the forward end of said motor including a feed drum rotatable on a vertical axis in advance of the rear end of said cutter bar.

7. In a mining machine, a horizontally disposed motor having a casing slidable directly on the mine bottom during cutting and an armature shaft, feeding means including a feed operating member driven by said motor and a cooperating controlling member, each of said members adapted to cooperate with flexible feeding means, and cutting mechanism driven by said armature shaft including a forwardly projecting cutter bar rigidly secured at the forward end of the machine frame in alignment with the latter and including a reciprocable controlling clutch therefor disposed coaxially with said armature shaft.

8. In a mining machine, a horizontally disposed motor, cutting mechanism driven by said motor including a forwardly projecting cutter bar, feeding means for the machine driven by the forward end of said motor comprising a feeding drum rotatable on a vertical axis in advance of the rear end of said cutter bar on the advancing side of the machine, and a controlling drum disposed at the rear of said motor.

9. In a mining machine, a motor having a casing slidable directly on the mine bottom during cutting and a longitudinally extending horizontal armature shaft, cutting mechanism driven thereby including a forwardly projecting cutter bar whose longitudinal axis is disposed parallel with the axis of said motor, and feeding mechanism driven by the forward end of said motor comprising a feed drum rotatable on a vertical axis in advance of the rear end of said cutter bar on the advancing side of the machine.

10. In a mining machine, a motor having a longitudinally extending horizontal armature shaft, cutting mechanism driven thereby including a forwardly projecting cutter bar whose longitudinal axis is disposed parallel with the axis of said motor, and feeding mechanism driven by the forward end of said motor comprising a variable speed device disposed on a vertical axis and a feed drum driven thereby and disposed on an axis spaced longitudinally of the machine from said axis of said device.
11. In a mining machine, a motor having a longitudinally extending horizontal armature shaft, cutting mechanism driven thereby including a forwardly projecting cutter bar whose longitudinal axis is disposed parallel with the axis of said motor, and feeding mechanism driven by the forward end of said motor comprising a variable speed device disposed on a vertical axis and a feed drum driven thereby disposed on an axis laterally offset from and parallel with the axis of said variable speed device.
12. In a mining machine, a horizontally disposed motor having an armature shaft, and feeding mechanism driven by the forward end of said motor comprising a worm secured to said armature shaft and driven thereby, a variable speed device disposed on a vertical axis, and spur gearing between said worm and said device.
13. In a mining machine, a horizontally disposed motor having a casing slidable directly on the mine bottom during cutting, cutting mechanism driven thereby, and feeding means for the machine driven by the forward end of said motor comprising a friction controlled variable speed device and a clutch associated with said device and including a clutch element reciprocable on a vertical axis and operating means for said clutch element operatively connected thereto at the upper end thereof.
14. In a mining machine, a horizontally disposed motor having a casing slidable directly on the mine bottom during cutting, cutting mechanism driven thereby including a lateral cuttings discharge passage, and feeding means driven by the forward end of said motor comprising a variable speed device disposed on a vertical axis adjacent the rear portion of said passage and a feed operating member driven by said device and arranged on the advancing side of the machine in advance of the rear portion of said cuttings passage.
15. In a mining machine, a horizontally disposed motor, cutting mechanism driven thereby including a lateral cuttings discharge passage, and feeding means driven by the forward end of said motor comprising a two speed friction controlled planetary device disposed on a vertical axis adjacent the rear portion of said passage and a feed operating member driven by said device and arranged on the advancing side of the machine in advance of the rear portion of said cuttings passage.
16. In a mining machine, a horizontally disposed motor, and feeding means for the machine driven by the forward end of said motor comprising a variable speed device and a drum driven thereby and rotatable on a vertical axis, and transmission gearing operatively connected to said device and disposed in horizontal planes above and below said variable speed device.
17. A mining machine having a substantially horizontal motor, the height of the machine being determined substantially by the height of the motor, cutting mechanism driven by said motor including a horizontal plane cutter, and feeding means for the machine including a planetary variable speed device disposed on a vertical axis, the upper surface of said cutter bar lying in a horizontal plane intersecting said motor and said planetary device.
18. In a mining apparatus, a machine frame having a projecting cutter bar, a motor on said frame having a casing having its bottom surface slidable directly on the mine bottom during cutting, and feeding means driven by said motor including a feed operating member rotatable on an axis perpendicular to the plane of said bar and adapted to cooperate with flexible feeding means, and planetary driving means for said feed operating member whose elements all rotate on axes laterally offset from and parallel to the axis of rotation of said feed operating member.
19. In a mining apparatus, a machine frame having a motor and a cutter bar, and feeding means driven by said motor including a feed operating member rotatable on an axis perpendicular to the plane of said bar and adapted to cooperate with flexible feeding means, and planetary driving means for said feed operating member whose elements all rotate on axes laterally offset from and parallel to the axis of rotation of said feed operating member and nearer said motor than said last mentioned axis.
20. In a mining machine, a motor comprising a casing slidable on its bottom on the mine bottom housing power producing means, the vertical dimension of said motor casing being substantially only that requisite to the power producing function of said motor and substantially determining the height of the machine, cutting mechanism driven by said motor and including a cutter bar whose uppermost and lowermost portions lie in planes parallel to a plane parallel to the bottom surface of said casing and intersecting said motor, and feeding mechanism driven by said motor and including a variable speed device disposed on a vertical axis, and a feed operating member driven thereby and adapted to

cooperate with flexible feeding means, said variable speed device and said feed operating member being arranged on spaced axes in planes adjacent the bottom surface of said motor casing.

21. In a mining machine, a motor comprising a casing housing power producing means and providing a surface slidably engageable with the mine bottom during cutting, the vertical dimension of said motor casing being substantially only that requisite to the power producing function of said motor and substantially determining the height of the machine, cutting mechanism driven by said motor and including a cutter bar whose uppermost and lowermost portions lie in planes parallel to a plane parallel to said bottom engaging frame surface and intersecting said motor, and feeding mechanism driven by said motor and including a variable speed device disposed on a vertical axis, and a feed operating member driven thereby and adapted to cooperate with flexible feeding means and disposed nearer the front end of the machine than said variable speed device.

22. In a mining machine, a motor comprising a casing housing power producing means and providing a surface slidably engageable with the mine bottom during cutting, the vertical dimension of said motor casing being substantially only that requisite to the power producing function of said motor and substantially determining the height of the machine, cutting mechanism driven by said motor and including a cutter bar whose uppermost and lowermost portions lie in planes parallel to a plane parallel to said bottom engaging frame surface and intersecting said motor, and feeding mechanism driven by said motor and including a variable speed device having two predetermined speeds frictionally controlled at each speed, said device being disposed on a vertical axis, and a feed operating member driven thereby and adapted to cooperate with flexible feeding means and disposed nearer the front end of the machine than said variable speed device.

23. In a mining machine, a machine frame providing a surface slidably engageable directly with the mine bottom during cutting, a motor housed in said frame, and feeding means driven by said motor including a variable speed device disposed on a vertical axis and having a plurality of predetermined speeds frictionally controlled at each speed, and a feed operating member adapted to cooperate with flexible feeding means driven thereby and rotatable about an axis laterally offset from and parallel with said axis of said device.

24. In a mining apparatus, a machine frame slidable on the mine bottom and having a horizontal motor and a forwardly projecting rigid cutter bar, and feeding means driven by said motor comprising a feed op-

erating member rotatable on an axis perpendicular to the plane of said bar and adapted to cooperate with flexible feeding means, and a variable speed device for driving said feed operating member and whose elements all rotate on axes laterally offset from and parallel to the axis of rotation of said feed operating member and having a plurality of predetermined speeds frictionally controlled at each speed.

25. In a mining apparatus, a horizontal motor having a casing slidable directly on the mine bottom during cutting, cutting mechanism driven from the forward end of said motor including a projecting cutter bar, and feeding mechanism driven from the forward end of said motor including a feed operating member rotatable on an axis perpendicular to the plane of said bar and adapted to cooperate with flexible feeding means, and planetary driving means for said feed operating member whose elements all rotate on axes laterally offset from and parallel to the axis of rotation of said feed operating member.

26. In a mining machine, a motor having a horizontal armature shaft, extending longitudinally of the machine, and feeding mechanism driven from the forward end of said armature shaft comprising a horizontal worm, a worm gear meshing therewith and rotatable on a vertical axis, a winding drum rotatable on an axis parallel to the axis of said worm gear, and a variable speed device having a plurality of predetermined speeds frictionally controlling each speed and disposed spatially longitudinally of the machine between said drum and worm gear and driven by the latter.

27. In a mining machine, a horizontal motor having a casing slidable directly on the mine bottom during cutting, cutting mechanism driven by said motor including a forwardly projecting cutter bar, and feeding means for the machine driven from the same end of said motor comprising a feed operating member adapted to cooperate directly with flexible feeding means and disposed on the advancing side of the machine in advance of the rear end of said cutter bar and a plural speed transmission mechanism therefor disposed at the rear of the rear end of said cutter bar and frictionally controlled at each speed, said transmission mechanism including a clutch member movable vertically in opposite directions to effect different speeds.

28. In a mining machine, a horizontal motor having a casing slidable directly on the mine bottom, the height of the motor substantially determining the height of the machine, cutting mechanism driven thereby from the forward end thereof, and feeding means for the machine driven by the same end of said motor comprising a feed operating member adapted to cooperate with flexi-

ble feeding means and a plural speed transmission mechanism therefor frictionally controlled at each speed and including a clutch member movable vertically in opposite directions to effect different speeds and operating means for said clutch member operatively connected thereto at the upper end thereof.

29. In a mining machine, a motor having a low compact casing slidable directly on the mine bottom and a horizontal armature shaft extending longitudinally of the machine, cutting mechanism driven from the forward end of said motor, and feeding mechanism driven from the same end of said motor comprising a feed operating member adapted to cooperate with flexible feeding means and a plural speed transmission mechanism therefor frictionally controlled at each speed and including a clutch member movable vertically in opposite directions to effect different speeds and operating means for said clutch member operatively connected thereto at the upper end thereof.

30. In a mining machine, a machine frame slidable on its bottom on the mine bottom, a horizontal motor carried thereby, cutting mechanism driven thereby, and feeding means driven by said motor comprising a plural speed transmission mechanism including coaxial gears rotatable about a vertical axis, a clutch member coaxial with said gears and movable vertically in opposite directions to effect different speeds and a single terminal element relative to which said clutch member is movable and through which all speeds are transmitted arranged coaxially with said gears, and a feed operating member driven by said motor through said transmission mechanism and including driving connections between the lower end of said transmission mechanism and said feed operating member including intermeshing reduction gearing, said feed operating member being adapted to cooperate with flexible feeding means.

31. In a mining machine, a horizontal low compact motor having a casing slidable directly on the mine bottom during cutting, cutting mechanism driven by said motor, and feeding means for the machine driven by said motor comprising a plural speed transmission mechanism including coaxial gears rotatable about a vertical axis, a clutch member coaxial with said gears and movable vertically in opposite directions to effect different speeds and a single terminal element relative to which said clutch member is movable and through which all speeds are transmitted arranged coaxially with said gears, and a feed operating member disposed on an axis spaced longitudinally from the axis of said gears driven by said motor through said transmission mechanism and adapted to cooperate with flexible feeding means.

32. In a mining machine, a horizontal low compact motor having a casing slidable directly on the mine bottom during cutting and having its armature shaft extending longitudinally of the machine, cutting mechanism driven from said motor, and feeding means driven from said motor comprising a plural speed transmission mechanism frictionally controlled at each of its speeds including coaxial gears arranged on a vertical axis, a clutch member coaxial with said gears and movable vertically in opposite directions to effect different speeds, and a single terminal element relative to which said clutch member is movable and through which all speeds are transmitted arranged coaxially with said gears, and a feed operating member rotatable about a vertical axis laterally offset from and parallel with the axis of said gears in advance of said transmission mechanism and driven by said motor through said transmission mechanism and adapted to cooperate with flexible feeding means.

33. In a mining apparatus, a machine frame having a projecting cutter bar, a motor on said frame having a casing having its bottom surface slidable directly on the mine bottom during cutting, and feeding means driven by said motor including a feed operating member adapted to cooperate with flexible feeding means and rotatable on an axis perpendicular to the plane of said bar, and plural speed planetary driving means for said feed operating member whose elements rotate on axes laterally offset from and parallel to the axis of rotation of said feed operating member and including a coaxial shiftable member movable vertically in opposite directions to effect different speeds.

34. In a mining apparatus, a machine frame having a motor and a cutter bar, and feeding means driven by said motor including a feed operating member rotatable on an axis perpendicular to the plane of said bar and adapted to cooperate with flexible feeding means, and planetary driving means for said feed operating member whose elements rotate on axes laterally offset from and parallel to the axis of rotation of said feed operating member and nearer said motor than said last mentioned axis, said planetary driving means including a coaxial shiftable member movable vertically in opposite directions to effect different speeds.

35. In a mining machine, a motor comprising a casing housing power producing means, the vertical dimension of said motor casing being substantially only that requisite to the power producing function of said motor and substantially determining the height of the machine, cutting mechanism driven by said motor including a cutter bar whose uppermost and lowermost portions lie in planes parallel to a plane parallel to the bottom

- surface of said casing and intersecting said motor, and feeding mechanism driven by said motor and including a variable speed device disposed on a vertical axis, and a feed operating member driven thereby and arranged with its axis offset laterally from the axis of said variable speed device and adapted to cooperate with flexible feeding means, said variable speed device including a coaxial shiftable member movable vertically in opposite directions to effect different speeds and said feed operating member being arranged on the advancing side of the machine in advance of said variable speed device.
36. In a mining machine, a motor comprising a casing housing power producing means, the vertical dimension of said motor casing being substantially only that requisite to the power producing function of said motor and substantially determining the height of the machine, cutting mechanism driven by said motor including a cutter bar whose uppermost and lowermost portions lie in planes parallel to a plane parallel to the bottom surface of said casing and intersecting said motor, and feeding mechanism driven by said motor and including a variable speed device disposed on a vertical axis and having two predetermined speeds frictionally controlled at each speed, and a feed operating member driven thereby and arranged with its axis offset laterally from the axis of said variable speed device and adapted to cooperate with flexible feeding means, said variable speed device including a coaxial shiftable member movable vertically in opposite directions to effect different speeds, and said feed operating member being arranged on the advancing side of the machine in advance of said variable speed device.
37. In a mining machine, a motor comprising a casing housing power producing means, the vertical dimension of said motor casing being substantially only that requisite to the power producing function of said motor and substantially determining the height of the machine, cutting mechanism driven by said motor and including a cutter bar whose uppermost and lowermost portions lie in planes parallel to a plane parallel to the bottom surface of said casing and intersecting said motor, and feeding mechanism driven by said motor and including a variable speed device disposed on a vertical axis, and a feed operating member driven thereby, said variable speed device and said feed operating member being so arranged that a horizontal plane intersects both of the same, and a cooperating controlling member, said members each being adapted to cooperate with flexible feeding means.

38. In a mining machine, a machine frame slidable on its bottom on the mine bottom, a motor carried thereby, cutting mechanism driven by said motor including a forwardly

projecting cutter bar, and flexible feeding means for feeding the machine bodily laterally over the mine bottom during cutting including advance and receding flexible feeding portions extending laterally in opposite directions from the opposite ends of said frame, and a cooperating feed operating member and a controlling member, said feed operating member being arranged on the advancing side of the machine in advance of the rear end of said cutter bar and acting on said advance flexible portion for effecting feed of the machine and said controlling member acting on said receding portion to effect control of the machine, and driving connections between said motor and said feed operating member including a planetary variable speed device disposed at the rear of the rear end of said cutter bar and whose elements rotate on vertical axes and having a plurality of speeds frictionally controlled at each speed.

39. In a mining machine, a low compact frame slidable on its bottom on the mine bottom and including a motor casing housing a motor, the vertical dimension of said motor determining the height of the machine, cutting mechanism driven by said motor including a horizontally projecting cutter bar, and flexible feeding means for feeding the machine bodily laterally over the mine bottom during cutting including an advance flexible feeding portion extending laterally from the forward end of said frame, and a feed operating member cooperating with said advance flexible portion, and driving connections between said motor and said feed operating member including a planetary variable speed device whose elements all rotate on vertical axes and having a plurality of speeds frictionally controlled at each speed, said feed operating member and said planetary device being so arranged upon the lower part of said frame that a horizontal plane intersects both of the same.

40. In a mining machine, a frame slidable on its bottom on the mine bottom, a motor carried thereby, cutting mechanism driven by said motor including a horizontally projecting cutter bar, and flexible feeding means for feeding the machine bodily laterally over the mine bottom during cutting including an advance flexible feeding portion extending laterally from the front end of the machine, and a cooperating feed operating member, and driving connections between said motor and said feed operating member including a planetary variable speed device disposed at the rear of the rear end of said cutter bar and arranged with its axis laterally offset from the axis of said feed operating member and whose elements all rotate on vertical axes and having a plurality of speeds frictionally controlled at each speed, said feed operating member being arranged on said frame in advance of said planetary device.

41. In a mining machine, a frame slidable on its bottom on the mine bottom, a motor carried thereby, cutting mechanism driven by said motor including a horizontally projecting cutter bar, and flexible feeding means for feeding the machine bodily laterally over the mine bottom during cutting and including an advance flexible feeding portion extending laterally from the front end of the machine and a cooperating feed operating member, and driving connections between said motor and said feed operating member including a variable speed mechanism arranged with its axis offset laterally from the axis of said feed operating member and including coaxial fast and slow speed driving members, a terminal driven member operatively connected to said feed operating member, and a clutch member coaxial with said driving members and shiftable vertically in opposite directions relative to said terminal member to effect rotation of the latter at different speeds.

42. In a mining machine, a machine frame slidable on its bottom on the mine floor, a motor carried at the rear end of said frame and having its power shaft horizontally disposed and extending longitudinally of the machine, cutting mechanism driven from the forward end of said power shaft including a forwardly projecting kerf cutter, and feeding means driven from the forward end of said power shaft including a frictionally controlled plural predetermined speed device disposed on a vertical axis and totally enclosed in said frame, a feed drum rotatably mounted on the exterior of said frame and adapted to cooperate directly with flexible feeding means, and driving connections between said plural predetermined speed device and said feed drum also enclosed within said frame.

43. In a mining machine, a machine frame slidable on its bottom on the mine floor, a motor carried by said frame at the rear end thereof and having its power shaft horizontally disposed and extending longitudinally of the machine, cutting mechanism driven from the front end of said power shaft including a forwardly projecting kerf cutter, and feeding means driven from the forward end of said power shaft including a frictionally controlled plural predetermined speed device disposed on a vertical axis, driving connections between said power shaft and the upper end of said device, a feed operating member adapted to cooperate directly with flexible feeding means and spaced longitudinally of the machine from said plural speed device, and driving connections between the lower end of said device and said feed operating member.

In testimony whereof I affix my signature.
